UNITED STATES PATENT OFFICE.

VERNON ROYLE, OF PATERSON, NEW JERSEY.

STRAINER HEAD FOR TUBING MACHINES.

Application filed December 26, 1918. Serial No. 347,569.

This invention relates to a strainer head for tubing machines with the object in view of providing a device of this character that will adapt the machine for satisfactory and expeditious operation upon materials of varying characteristics without producing an undue strain upon any of the parts or irregularity in the operation.

Another object is to provide a device of this character, which is calculated to increase the output of the machine.

Another object consists in providing a device of this character, which may be easily and quickly assembled for operation and disassembled for cleaning, repair or replacement.

Another object consists in providing certain improvements in the form, construction and arrangement of the several parts whereby the above named and other objects may be effectively attained.

Machines of this character are designed to operate upon rubber compounds including various substances during the process of reclaiming the rubber and these materials vary greatly in consistency. Consequently, it has been found that strainer heads heretofore in use have not been fully adequate to handle these different materials with satisfactory results in all respects. My invention is designed to overcome this disadvantage.

A practical embodiment of the invention is represented in the accompanying drawings, in which,

Fig. 1 represents a face elevation of the device partly broken away.

Fig. 2 represents a longitudinal section taken in the plane of the line II—II of Fig. 1, looking in the direction of the arrows.

Fig. 3 represents a transverse section taken in the plane of the line III—III of Fig. 2, looking in the direction of the arrows.

Fig. 4 represents a detail transverse section taken in the plane of the line IV—IV of Fig. 2, looking in the direction of the arrows.

Fig. 5 represents a fragmentary section taken in the plane of the line V of Fig. 3, looking in the direction of the arrow.

Fig. 6 represents a view similar to Fig. 5, with certain parts in different positions.

The strainer head is adapted for use in connection with a tubing machine of standard or appropriate form and is, as will be

understood by operatives in this industry, intended to be secured to the cylinder of the tubing machine in which the screw or plodder operates.

In the present instance, the cylinder is denoted by 1 and the liner for its bore by 2. The screw or plodder which operates in the said bore in the usual manner is indicated by 3.

The strainer head includes an inner tubular member 4, which is flanged and threaded on its inner end for engagement with the interiorly threaded end of the bore liner 2, as clearly indicated at 5. The arrangement is such that the inner end of the member 4 abuts a shoulder on the bore liner 2, while the forward end of the latter abuts the flange on the member 4, thereby establishing a firm inter-engagement, with the interior of the member 4 in precise alinement with the bore of the liner 2. As a result of this arrangement, the inner member 4 constitutes, in effect, a forward extension of the cylinder bore in which the forward end of the plodder 3 is designed to operate. It is convenient, from a manufacturing point of view, to have the member 4 secured to the bore liner 2 as described, but this is not essential and it might be advisable in many cases to form the member 4 integral with the liner 2.

The part of the member 4, which protrudes from the cylinder 1, is provided with a multiplicity of small circular perforations 6 and the front end of the said member is open.

The head also includes an outer member or jacket 7 that is also cylindrical in form and has its walls provided with perforations 8, that are similar in cross section to the perforations 6 in the inner member 4.

The outer member 7 has its front end provided with an exteriorly threaded rim 9, which is fitted to be engaged by a locking nut 10. An end plate 11 fits within the front end of the outer member 7 and is held in position by being clamped between the front end of the inner member 4 and the nut 10. This end plate 11 also has a large number of circular perforations 12 formed therethrough and it will be observed that these perforations are greater in cross section at their outer part than at their inner part. The arrangement of all the perforations described is such that those in the tubular

members 4 and 7 lie at right angles to the axis of the screw 3, while those in the end plate 11 are parallel to the axis of the screw.

5 The inner diameter of the outer member 7 is somewhat greater than the outer diameter of the inner member 4, so that a space 13 is left between the said members when the outer is put over the inner, like a jacket, 10 as clearly shown in Fig. 2, and a cylindrical screen or netting 14 is located between the said members 4 and 7 and against the interior of the outer member 7. A flat screen 15 is located against the inner face of the 15 end plate 11 and is clamped in position between the said plate and the inner member 4. It will be noted that as the end member 11 is fitted within the front end of the outer member 7 and clamped by the locking nut 20 to the front end of the inner member 4, the members 4 and 7 are in spaced relation at their front ends, while a spacing ring 16 is located between the members 4 and 7 25 at their rear ends in order to hold them in spaced relation at this point.

It is desirable in many cases to have the perforations 6 and 8 in the inner and outer tubular members 4 and 7 in exact alignment for the proper operation of the machine 30 and, in order to effect this alignment and assure its retention, I provide a dowel 17 that projects from the flange on the rear part of the member 4 and is calculated to enter a corresponding recess 18 formed in 35 the rear end of the outer member 7. When the dowel enters the recess, the inner and outer members have their perforations in exact alignment.

My invention includes means for firmly 40 securing the outer member 7 and parts carried thereby to the cylinder 1 in operative position and for permitting the expeditious removal or detachment thereof for any desired purpose. This means includes an annular plate 19, which has a series of circumferentially elongated slots 20, that are designed to receive stud bolts 21, which are threaded into and project from the front end of the cylinder 1. These arcuate slots 50 20 permit the plate 19 to be moved in a rotary direction a short distance on the bolts 21, and suitable nuts 22 serve to secure the plate 19 in any desired position with respect to the bolts 21. The inner edge of the plate 55 19 is cut away as indicated at 23, thereby forming a rib 24. A clamping ring 25 has its outer periphery fashioned to correspond with the recess and rib 23, 24, on the plate 19, and is adjustably and removably secured 60 to the plate 19 by clamps 26, which are pierced by cap screws 27 threaded into the ring 25. The operation of the clamps is to grip the rib 24 on the plate 19 between the complementary part on the outer periphery of the ring 25 and the clamps, so as to

frictionally hold the ring 25 in engagement with the plate 19.

The inner periphery of the ring 25 has a series of segmental lugs 28 formed thereon, which overlap and mate with a corresponding series of segmental lugs 29, which project outwardly from the rear end of the outer tubular member 7. These lugs 28, 29, have their sides cut on radial lines and the lugs 29 are of such size and form that they can enter the spaces between the lugs 28. This construction enables the outer tubular member 7 to be slid axially rearwardly with respect to the locking ring 25, during which movement the lugs 29 pass between the lugs 28. With the parts in this position and with the nuts 22 on the bolts 21 slightly loosened, the plate 19 and locking ring 25 carried thereby may be moved in a circumferential direction until the lugs 28 pass over and register with the lugs 29, thereby locking the tubular member 7 in place on the cylinder 1. It will be observed that the slots 20 in the plate 19 are of such length as to just about permit circumferential movement of the plate 19 adequate to move the lugs 28 from locking position in front of the lugs 29 to unlocking position in line with the openings between the lugs 29, and an equivalent movement in the opposite direction is also, of course, permitted. Hence, to detach the outer member 7 and parts carried thereby, it is simply necessary to insert a spike in the socket 30 fashioned in the periphery of the plate 19, loosen the nuts 22, and then swing the said plate until the free ends of the slots 20 engage the bolts 21. In this position, the tubular member 7 may be removed by an axial forward movement. To replace the said parts, the member 7 is slid rearwardly in an axial direction and the plate 19 swung circumferentially until the opposite ends of the slots 20 again engage the bolts 21; after which the nuts 22 may be tightened for securing the parts in place. During this movement of the plate 19, the ring 25 moves with it and acts as a part thereof. However, in case the bolts 21 or slots 20 should be slightly misplaced in their operative relationship with respect to the outer tubular member 7, or, if for any other reason, the lugs 28 should not exactly coincide with the lugs 29 when the plate 19 is turned so that the bolts 21 abut one end of the slots 20 and exactly in line with the spaces between the lugs 29 when the other ends of the slots 20 abut the bolts 21, such discrepancy may be compensated by loosening the screws 27 that hold the clamps 26 in position and moving the locking ring 25 circumferentially a suitable distance in the proper direction with respect to the plate 19. When this movement has caused the lugs 28 to come into the proper position with respect to the lugs 29, the screws 27

- may be tightened, thereby causing the clamps 26 to firmly lock the ring 25 to the plate 19.
- As already described, there is a space between the inner tubular member 4 and the outer member 7, while the screen 13 is also spaced from the inner member 4. As a result of this construction, the material being operated upon is broken up by the holes 6 in the inner member 4 and permitted to surge or eddy around a little between the inner and outer members before passing through the screen 13. This protects the screen and renders it more durable and effective, as well as avoiding the clogging thereof for a longer period of time. By perforating the entire walls of the members 4 and 7, the outlet for material is greatly increased, thus increasing the capacity of the machine. By increasing the cross sectional size of the outer part of the holes 12 in the end plate 11, the material is allowed to expand as it passes therethrough, thus decreasing the resistance and hence increasing the output of the machine.
- It will be understood that various changes may be resorted to in the form, construction and arrangement of the several parts without departing from the spirit and scope of my invention, and hence I do not intend to be limited to the details herein shown and described, except as they may be included in the claims.
- What I claim is:
1. A device of the character described comprising, a tubular element composed of inner and outer members having each of their walls provided with a multiplicity of holes, the inner member being spaced from the outer member, said holes in the members being disposed substantially in alinement.
  2. A device of the character described comprising, a tubular element composed of inner and outer members having their walls provided with a multiplicity of holes disposed substantially in alinement, the inner member being spaced from the outer member, and a cylindrical screen adjacent the interior of the outer member and spaced from the inner member.
  3. A device of the character described comprising, a tubular element composed of inner and outer members, a separable end member for said element, all said members being provided with a multiplicity of holes, said holes in the inner and outer members being substantially in alinement, a cylindrical screen intermediate the inner and outer members and spaced from the inner member, and a flat screen intermediate the inner and end members.
  4. A device of the character described comprising, a tubular element composed of inner and outer perforated members, means interposed between them at their rear ends for holding them in spaced relation, and a separable perforated end member for said element, said outer and end members being detachably secured in position.
  5. A device of the character described comprising, a tubular element composed of inner and outer perforated members, spacing means interposed between said members, and a separable end member seated within the outer member and in abutment with the inner member.
  6. A device of the character described comprising, a tubular element composed of inner and outer members, spacing means interposed between said members, a separable end member seated within the outer member and in abutment with the inner member, and means engaging the outer member for securing the end member in position.
  7. A device of the character described comprising, a tubular element composed of inner and outer members, spacing means interposed between said members, a separable end member seated within the outer member and in abutment with the inner member, and a nut engaging the outer member for securing the end member in position.
  8. A device of the character described comprising, a tubular element composed of inner and outer members, spacing means interposed between one end of the members, said members being perforated, and a device carried by the one member and fitted to engage the other for positioning the one member with respect to the other with the perforations in each member in a predetermined relation with respect to the perforations in the other member.
  9. A device of the character described comprising, a tubular element composed of inner and outer members, spacing means interposed between one end of the members, said members being perforated, one of said members being provided with a dowel and the other member with a recess adapted to receive the dowel for positioning the one member with respect to the other with the perforations in each member in a predetermined relation with respect to the perforations in the other member.
  10. In apparatus of the character described, a tubular strainer head and means movable in a rotary direction around the plodder for attaching the strainer head to the cylinder of the machine.
  11. In apparatus of the character described, a tubular strainer head, and means movable in a rotary direction around the plodder for attaching and detaching the strainer head to and from the cylinder of the machine.
  12. In apparatus of the character described, a tubular strainer head, and means for attaching the strainer head to the cylinder of the machine, said means including

- a plate provided with elongated slots, and projections on the cylinder fitted to enter said slots, whereby the plate may be moved in a rotary direction around the plodder.
- 5 13. In apparatus of the character described, a tubular strainer head, means for attaching the strainer head to the cylinder of the machine, said means including a plate provided with circumferentially elongated 10 slots, projections on the cylinder fitted to enter said slots, whereby the plate may be moved in a rotary direction around the plodder, and means for locking the plate in any desired position.
- 15 14. In apparatus of the character described, a tubular strainer head, and means for attaching the strainer head to the cylinder of the machine, said means including a radially arranged projection on the strainer 20 head and a plate secured to the cylinder and having a cut away portion for the passage of the projection therethrough, said plate being adapted to engage said projection adjacent said cut away portion.
- 25 15. In apparatus of the character described, a tubular strainer head, and means for attaching and detaching the strainer head to and from the cylinder of the machine, said means including inwardly projecting lugs on the strainer head, and a plate secured to the cylinder carrying outwardly 30 projecting lugs designed to mate with the lugs on the head.
16. In apparatus of the character described, a tubular strainer head and means for attaching and detaching the strainer head to and from the cylinder of the machine, said means including inwardly projecting lugs on the strainer head, and a plate 35 secured to the cylinder carrying outwardly projecting lugs designed to mate with the lugs on the head, said plate being movable in a rotary direction to bring its lugs in line with and out of line with the lugs on the head.
- 40 17. In apparatus of the character described, a strainer head and means for attaching and detaching the strainer head to and from the cylinder of the machine, said means including lugs on the strainer head, a plate secured to the cylinder carrying lugs 45 designed to mate with the lugs on the head, said plate being movable in a rotary direction to bring its lugs in line with and out of line with the lugs on the head, and means for locking the plate in any desired position.
18. In apparatus of the character described, a strainer head and means for attaching and detaching the strainer head to and from the cylinder of the machine, said means including lugs on the strainer head, a plate secured to the cylinder, a member 55 carried by the plate and rotatably adjustable with respect thereto, said member having lugs designed to mate with the lugs on the head, said plate being movable in a rotary direction to bring its lugs in line with and out of line with the lugs on the head, and means for locking the plate in any desired position.
- 60 19. In apparatus of the character described, a strainer head and means for attaching and detaching the strainer head to and from the cylinder of the machine, said means including lugs on the strainer head, a plate carried by the cylinder, a locking ring carried by the plate and having lugs 65 designed to mate with the lugs on the head, the said plate being movable in a rotary direction with respect to the cylinder and the said locking ring being movable in a rotary direction with respect to the plate.
20. In apparatus of the character described, a strainer head and means for attaching and detaching the strainer head to and from the cylinder of the machine, said means including lugs on the strainer head, a plate carried by the cylinder, a locking ring carried by the plate and having lugs 70 designed to mate with the lugs on the head, the said plate being movable in a rotary direction with respect to the cylinder, the said locking ring being movable in a rotary direction with respect to the plate, and means for locking the plate and ring in any desired position.
21. In apparatus of the character described, a strainer head and means for attaching and detaching the strainer head to and from the cylinder of the machine, said means including lugs on the strainer head, a plate carried by the cylinder, a locking ring carried by the plate and having lugs 75 designed to mate with the lugs on the head, the said plate being movable in a rotary direction with respect to the cylinder, the said locking ring being movable in a rotary direction with respect to the plate, said ring and said plate overlapping each other, and a clamp carried by the one and engaging the other for locking the said plate and ring in any desired adjustment with respect to each other.
22. In apparatus of the character described, a strainer head and means for attaching and detaching the strainer head to and from the cylinder of the machine, said means including lugs on the strainer head, a plate carried by the cylinder, a locking ring carried by the plate and having lugs 80 designed to mate with the lugs on the head, the said plate being movable in a rotary direction with respect to the cylinder, the said locking ring being movable in a rotary direction with respect to the plate, said ring and said plate overlapping each other, a clamp carried by the one and engaging the other for locking the said plate and ring in any desired position.
- 85 23. In apparatus of the character described, a strainer head and means for attaching and detaching the strainer head to and from the cylinder of the machine, said means including lugs on the strainer head, a plate carried by the cylinder, a locking ring carried by the plate and having lugs 90 designed to mate with the lugs on the head, the said plate being movable in a rotary direction with respect to the cylinder, the said locking ring being movable in a rotary direction with respect to the plate, and means for locking the plate and ring in any desired position.
- 95 24. In apparatus of the character described, a strainer head and means for attaching and detaching the strainer head to and from the cylinder of the machine, said means including lugs on the strainer head, a plate carried by the cylinder, a locking ring carried by the plate and having lugs 100 designed to mate with the lugs on the head, the said plate being movable in a rotary direction with respect to the cylinder, the said locking ring being movable in a rotary direction with respect to the plate, said ring and said plate overlapping each other, and a clamp carried by the one and engaging the other for locking the said plate and ring in any desired adjustment with respect to each other.
- 105 25. In apparatus of the character described, a strainer head and means for attaching and detaching the strainer head to and from the cylinder of the machine, said means including lugs on the strainer head, a plate carried by the cylinder, a locking ring carried by the plate and having lugs 110 designed to mate with the lugs on the head, the said plate being movable in a rotary direction with respect to the cylinder, the said locking ring being movable in a rotary direction with respect to the plate, said ring and said plate overlapping each other, and a clamp carried by the one and engaging the other for locking the said plate and ring in any desired position.
- 115 26. In apparatus of the character described, a strainer head and means for attaching and detaching the strainer head to and from the cylinder of the machine, said means including lugs on the strainer head, a plate carried by the cylinder, a locking ring carried by the plate and having lugs 120 designed to mate with the lugs on the head, the said plate being movable in a rotary direction with respect to the cylinder, the said locking ring being movable in a rotary direction with respect to the plate, said ring and said plate overlapping each other, a clamp carried by the one and engaging the other for locking the said plate and ring in any desired position.

adjustment with respect to each other, and means for locking the plate in any desired adjustment with respect to the cylinder.

23. In apparatus of the character described, a strainer head, and means for attaching and detaching the strainer head to and from the cylinder of the machine, said means including lugs on the strainer head having their sides radially disposed, and a plate secured to the cylinder carrying lugs designed to mate with the lugs on the head.

24. In apparatus of the character described, a strainer head and means for attaching and detaching the strainer head to and from the cylinder of the machine, said means including lugs on the strainer head having their sides radially disposed, and a plate secured to the cylinder carrying lugs designed to mate with the lugs on the head, said plate being movable in a rotary direction to bring its lugs in line with and out of line with the lugs on the head.

25. In apparatus of the character described, a strainer head and means for attaching and detaching the strainer head to and from the cylinder of the machine, said means including lugs on the strainer head having their sides radially disposed, a plate secured to the cylinder carrying lugs designed to mate with the lugs on the head, said plate being movable in a rotary direction to bring its lugs in line with and out of line with the lugs on the head, and means for locking the plate in any desired position.

26. In apparatus of the character described, a strainer head and means for attaching and detaching the strainer head to and from the cylinder of the machine, said means including lugs on the strainer head having their sides radially disposed, a plate secured to the cylinder and having rotatably adjustable lugs designed to mate with the lugs on the head, said plate being movable in a rotary direction to bring its lugs in line with and out of line with the lugs on the head, and means for locking the plate in any desired position.

27. In apparatus of the character described, a strainer head and means for attaching and detaching the strainer head to and from the cylinder of the machine, said means including lugs on the strainer head having their sides radially disposed, a plate secured to the cylinder and having rotatably adjustable lugs designed to mate with the lugs on the head, said plate being movable in a rotary direction to bring its lugs in line with and out of line with the lugs on the head, means for locking the plate in any desired position, with respect to the cylinder, and means for securing said rotatably adjustable lugs in any desired adjustment with respect to the plate.

28. In apparatus of the character described, a strainer head and means for at-

taching and detaching the strainer head to and from the cylinder of the machine, said means including lugs on the strainer head having their sides radially disposed, a plate carried by the cylinder, a locking ring carried by the plate and having lugs designed to mate with the lugs on the head, the said plate being movable in a rotary direction with respect to the cylinder and the said locking ring being movable in a rotary direction with respect to the plate.

29. In apparatus of the character described, a strainer head and means for attaching and detaching the strainer head to and from the cylinder of the machine, said means including lugs on the strainer head having their sides radially disposed, a plate carried by the cylinder, a locking ring carried by the plate and having lugs designed to mate with the lugs on the head, the said plate being movable in a rotary direction with respect to the cylinder, the said locking ring being movable in a rotary direction with respect to the plate, and means for locking the plate and ring in any desired adjustment.

30. In apparatus of the character described, a strainer head and means for attaching and detaching the strainer head to and from the cylinder of the machine, said means including lugs on the strainer head having their sides radially disposed, a plate carried by the cylinder, a locking ring carried by the plate and having lugs designed to mate with the lugs on the head, the said plate being movable in a rotary direction with respect to the cylinder, the said locking ring being movable in a rotary direction with respect to the plate, said ring and said plate overlapping each other, and a clamp carried by the one and engaging the other for locking the said plate and ring in any desired adjustment with respect to each other.

31. In apparatus of the character described, a strainer head and means for attaching and detaching the strainer head to and from the cylinder of the machine, said means including lugs on the strainer head having their sides radially disposed, a plate carried by the cylinder, a locking ring carried by the plate and having lugs designed to mate with the lugs on the head, the said plate being movable in a rotary direction with respect to the cylinder, the said locking ring being movable in a rotary direction with respect to the plate, said ring and said plate overlapping each other, a clamp carried by the one and engaging the other for locking the said plate and ring in any desired adjustment with respect to each other, and means for locking the plate in any desired adjustment with respect to the cylinder.

32. A device of the character described comprising, a tubular element composed of

inner and outer perforated members, a perforated end member for said element, means for removably securing the end member to the outer member, said outer member being provided at its rear end with lateral projections, which said projections are adapted to be moved into and out of engagement with projections on the tubing machine for bringing the outer member and end member into and out of operative position with respect to the machine.

33. A device of the character described comprising, a tubular element including a

perforated member, and a cylindrical screen exterior to said member and spaced therefrom.

34. A device of the character described comprising, a tubular element including perforated inner and outer members arranged in spaced relation, and a cylindrical screen intermediate the members and spaced from the inner member.

In testimony, that I claim the foregoing as my invention, I have signed my name this seventeenth day of December, 1919.

VERNON ROYLE.
